ROTARY BLADE SAFETY RAZOR

Ernest Charles Garrard, Maidenhead, and Kenneth Harrold, Taplow, England, assignors to The Fairey Aviation Company Limited, Hayes, England

Application January 4, 1949, Serial No. 69,096
In Great Britain January 29, 1948

2 Claims. (Cl. 30—43)

1

This invention relates to a safety razor of the type in which a bladed rotary member is arranged to be revolved within a head which may be of cylindrical or other shape and is formed longitudinally with a slot, one side of which is sharpened to constitute a fixed cutting edge and the opposite side of which is of comb-like configuration to constitute a safety guard.

In some razors of this type it is necessary to provide means for adjusting the eccentricity of the axis of the rotary member relatively to that of the cylinder to ensure a predetermined degree of cut, and proposals have been made to provide such means for pre-setting by the manufacturer. With such means it is not possible, however, for the degree of cut, e. g., "coarse," "medium" or "fine," to be pre-selected or varied by the user.

To overcome this, and to provide means readily operable by the user, we have, in the specification of our co-pending United States applications Serial Nos. 775,690 and 87,266, now Patent Nos. 2,594,764 and 2,586,022 respectively, shown a head, for a safety razor of the type described, in which the inner peripheral dimension of the head can be expanded or contracted by the user so as to vary the width of the axial gap in the head within which the rotary bladed member revolves. The desired dimensional adjustment may be effected, for instance, by movement axially in relation to the head of a wedge, by rotation in the head of an eccentric, or by moving towards or away from one another tongues projecting from the head at opposite sides of the slot where its cutting edge is formed.

The axis of rotation of the rotary bladed member always maintains a fixed position relatively to the fixed cutting edge, variation of the width of the axial gap being attained by movement of the comb.

In these and other constructions described and illustrated in our said specification, the head has been formed in one piece, which has been sprung to vary the width of the axial gap by virtue of the inherent springiness of the material from which the head has been formed. We have now found that in some designs of head this has resulted in the introduction of secondary distortions tending to bow the fixed blade. While it is possible to overcome or prevent such distortions by local weakening of the head, such methods are not always desirable, and we have therefore evolved a modified form of head to obviate the introduction of such secondary distortions.

According to the present invention, a head for a safety razor of the type hereinbefore described, provided with means readily operable by the user

for expanding and/or contracting the inner peripheral dimension of said head, is formed in two parts arranged to be hinged along an axis parallel with and substantially diametrically opposite the axial slot in the head.

The hinge may comprise interdigitated tongues formed on the two parts and apertured to receive a hinge pin, or alternatively it may comprise a knife-edge formed on one of the parts and a groove, arranged to receive the knife-edge, formed in the other part. Spring means may be provided to urge the two parts toward one another.

The expansion and contraction of the head may be controlled by an eccentric cam rotatable about an axis parallel with the longitudinal axis of the head. Such a cam may comprise a pivoted selector bar provided with a pin or like member arranged to engage an eccentric cam groove formed in the head.

Another form of cam may comprise a disc concentrically arranged within the head and rotatable relatively thereto, the head being formed with a projection directed radially inwardly, and the disc being formed with two or more circumferentially spaced recesses of progressively varying size arranged to engage the projection in different angular positions of the disc, one or more of the recesses being smaller than the projection.

The expansion and contraction of the head may, alternatively, be controlled by a wedge member movable axially relatively to the head. The wedge member may comprise a block having fixed pins arranged to be movable in grooves in the head extending in the general direction of the axis of the head and converging towards one another. In another form, the wedge member may comprise a plate formed with convergent slots arranged to engage pins secured to the head.

Several embodiments of the invention will be described with reference to the accompanying drawings, which for convenience are larger than full-size, and in which:

Figure 1 is a perspective view of one form of razor head.

Figure 2 is a fragmentary perspective view of a hinge.

Figure 3 is a fragmentary diagrammatic sectional plan showing a selector bar engaging the end of the head.

Figure 4 is a diagrammatic end elevation of another head showing a further form of hinge,

Figure 5 is a fragmentary perspective view of yet another form of head,

Figure 6 is an end elevation of the head in the open position.

Figure 7 is a diagrammatic end elevation of a further form of head.

Figure 8 is a fragmentary perspective view of a wedge means for controlling a head.

Figure 9 is an end elevation of the wedge member shown in Figure 8.

Figure 10 is a fragmentary perspective view of another form of wedge means for controlling a head, and

Figure 11 is a perspective view of the wedge member of Figure 10, showing the other side.

Referring to Figures 1, 2 and 3, a hollow cylindrical razor head 12 is formed longitudinally with a slot 13, at one side of which there is a fixed cutting edge 14 and at the opposite side of which there is formed a comb-like construction 15 to constitute a safety guard. Within the head 12 a bladed rotary member is mounted on a spindle 16 carried in bearings 17 each housed in a slotted disc 18.

The head 12 is formed in two parts, 12^a and 12^b, formed with interdigitated tongues 12^c, 12^d as shown in Figure 2, the tongues being apertured to receive a hinge pin 19. Around the ends of the head 12 C-shaped springs 20, 21 which embrace the hinged parts 12^a, 12^b of the head and tend to force them together may be fitted, the hinged parts in turn embracing the discs 18.

Mounted on pivots 22 on the part 12^b of the head is a selector bar 23, which carries at each end a pin 24 projecting into a cam groove 25 formed in the part 12^a of the head. This groove is formed eccentrically relatively to the arc struck by the pin 24 turning about the centre 22, and is arranged so that as the selector bar 23 and pin 24 move across the end of the head 12 from left to right, as viewed in Figure 1, the upper part 12^a of the head is brought nearer to the lower part 12^b, turning about its hinge pin 19 and so bringing its edge 15 nearer the edge 14 of the lower part 12^b. The axial gap is thus decreased in width.

The part 12^a of the head is formed with three radially extending circumferentially spaced grooves 26, 27 and 28, and the selector bar 23 is formed with a rib 23^a extending along the inner sides of its ends and capable of being sprung into or out of any of the grooves 26, 27 and 28. In this way different settings of the head may be readily obtained by the user.

It is to be noted that the C-springs 20, 21 are an optional feature. If desired, movement of the part 12^a relatively to the part 12^b may be controlled entirely by the selector bar 23, pin 24, and groove 25.

In Figure 4 there is shown an alternative method of hinging the parts 12^a and 12^b of the head. Instead of having interdigitated tongues, these parts are formed with a knife-edge 29 and a V-groove 30, respectively, extending along the length of the head the parts being urged by C-springs 20 as before.

In Figures 5 and 6 there is shown a modified construction, the upper part of the head 12, termed 112^a, being provided at each end with a cam plate 31 secured by rivets or other suitable means, and formed with a slot 32 similar in general shape to the groove 25 of the previous embodiment. The selector bar 23 has at each end a pin 24 located so as to be in the slot 32, and by movement of the selector bar about its pivot 22 the position of the pin 24 in the slot 32, and hence the width of the axial gap 13, can be varied. The

part 112^a of the head 12 is formed at each end with depressions 33, 34, 35 into which the pin 24 may be sprung to retain the selector bar 23 in the selected position.

Figure 6 shows how the selector bar 23 and upper part 112^a of the head may be swung away (after removal of the C-springs 20 and 21, if fitted) to allow access to the rotary bladed member (not shown), e. g. for cleaning.

In the construction shown in Figure 7, the head is formed of two hinged parts, 12^b and 36, the latter being formed at each end with a pip 37. A disc 38 is formed with three circumferentially spaced notches 39, 40 and 41 of successively decreasing size, the largest notch being just large enough to accommodate the pip 37. The discs 38 are secured to the ends of a selector bar 42.

When the pip 37 is in the notch 39, the parts 36 and 12^b are held by the spring 20 to embrace the disc 38 closely, and the width of the axial gap 13 is at a minimum. When the selector bar 42 is turned so as to bring the notch 40 opposite the pip 37, only the end of the pip is accommodated, as shown in Figure 7, and so the width of the axial gap 13 is increased. When the pip 37 engages the smallest notch 41 the width is still further increased.

In Figures 8 and 9 there is shown an embodiment in which the parts 43, 44 of the head, hinged at 19 as before and embraced by springs 20, are formed with converging grooves 45, 46, which receive pins 47 projecting from a wedge member 48 provided with a stud 49 slidable in a guide-way 50 in the head. Axial movement of the wedge member 48 enables the hinged parts 43, 44 to be adjusted as required to provide a setting of the width of the axial gap 13, the slotted disc 18 being attached to the part 44.

Figures 10 and 11 illustrate a modification of this construction, the wedge member 48^a having a plate 51 formed with converging slots 45^a, 46^a in which pins 53, 54 projecting from the parts of the head are arranged to be slidable. The plate 51 has a rib 52 riding in the axial gap 13 and acting as a locating member for the plate. As in the previous embodiment, axial movement of the wedge member 48^a enables the setting of the width of the axial gap 13 to be adjusted.

In both embodiments described with reference to Figures 8 to 11, axial movement of the pairs of wedges 48 or 51 is co-related by the user sliding the head in taper slots provided on a convenient portion of the razor container or the like, as described in the specification of our co-pending applications.

We claim:

1. A head for a safety razor formed with a tunnel and having a bladed rotary cutting element arranged to be revolved in the tunnel, said head comprising a first member having a cutting edge, a second member having a safety guard, said first and second members being hinged to permit adjustment of the relative position of said cutting edge and said safety guard to form a slot therebetween, one of said members being formed with an eccentric cam groove and the other member having a pivoted selector bar provided with pin means for engaging the eccentric cam groove, movement of the selector bar about its pivot controlling the expansion and contraction of the head.

2. A head for a safety razor formed with a tunnel and having a bladed rotary cutting element arranged to be revolved in the tunnel, said head comprising a first member having a cutting

edge, a second member having a safety guard, said first and second members being hinged to permit adjustment of the relative position of said cutting edge and said safety guard to form a slot therebetween, one of said members being formed with a cam groove disposed tangentially of the periphery of said rotary cutter, and the other member having a pivoted selector bar provided with pin means for engaging the eccentric cam groove, movement of the selector bar about its pivot controlling the expansion and contraction of the head.
